GRINDING WHEEL DRESSER

Filed March 6, 1945

UNITED STATES PATENT OFFICE

2,442,172

GRINDING WHEEL DRESSER

Carl O. Klockars, Slatersville, R. I.

Application March 6, 1945, Serial No. 581,213

1 Claim. (Cl. 125—11)

1

This invention relates to a diamond holder, and more particularly to such a diamond holder adapted for use with diamonds adapted for dressing emery wheels on surface grinders, or the like.

A primary object of this invention is the provision of an improved diamond holder provided with means whereby the diamond, or diamonds, associated therewith may be adjusted both as to height, and as to angular inclination, with respect to an emery wheel or the like to be dressed, in such manner that various sizes and heights of wheels may be readily dressed with a minimum of effort, fatigue and time.

An additional object of this invention is the provision of such a diamond holder provided with means whereby the diamond or diamonds associated therewith may be readily positioned at any desired angle or height as desired.

A further object of the invention is the provision of such a device which will be sturdy and durable in construction, reliable and efficient in operation, and relatively simple and inexpensive to manufacture, assemble, and utilize.

Other objects will in part be obvious and in part be pointed out as the description of the invention proceeds, and shown in the accompanying drawings wherein there is disclosed a preferred embodiment of this inventive concept.

In the drawings:

Figure 1 is a side elevational view of one form of diamond holder embodying this inventive concept,

Figure 2 is an end elevational view of the device disclosed in Figure 1, and

Figure 3 is a top plan view of the device.

Similar reference characters refer to similar parts throughout the several views of the drawings.

Having reference to the drawings, there is shown at 10 a base plate, adapted to be positioned on a magnetic chuck 11, from which base a cylindrical post 12 extends upwardly a desired distance. A bracket, generally indicated at 13, including a cylindrical bore 14 and bifurcations 15, is positioned about the post 12.

The bifurcations 15 are provided with aligned threaded apertures, through which is passed a bolt 16, provided with an ear or operating handle 17, the arrangement being such that movement of the handle 17 serves to turn the bolt 16 to clamp the bifurcations 15, and the bore 14 securely in any desired angular relation, or at any desired height upon the post 12.

The member 13 includes a depending portion 20, adapted to extend and overlie the base 10 and

2

terminate at a point adjacent the chuck 11. The portion 20 has a transversely extending bore 21 therethrough adapted to contain a diamond holder 22, the latter being held in position as by a set screw 23.

Extending outwardly from the depending portion 20 is a horizontal portion 24 provided with a vertical bore 25 adapted to contain a diamond holder 26, the latter being held in position as by a horizontally positioned set screw 27.

Thus it will be seen that the bracket 13 is provided with two diamond holders, one in a horizontal position, and the other in a vertical position, adapted to operate upon either the side or the face of an emery wheel, generally indicated at 30. From the foregoing, it will now be readily apparent that the angular relation of the bracket 13 and hence that of either of the diamond holders 22 or 26 may be readily varied by movement 20 of the handle 17, and consequent loosening of the bifurcations 15, permitting the bracket 13 to be readily rotated about the post 12. Correspondingly, it will be seen that a similar operation will permit the member 13 to be positioned at any 25 desired height on the post 12 as desired, to accommodate any size or type of emery wheel as may be necessary.

Either or both diamond holders may, if desired, be provided with micrometer threads to permit 30 precision adjustment, as when duplicate parts are being ground.

Now, from the foregoing, it will be seen that there is herein provided a device accomplishing all of the objects of this invention and others, 35 including many advantages of great practical utility and commercial importance.

As many embodiments may be made of this inventive concept, and as many modifications may be made in the embodiment hereinbefore 40 shown and described, it is to be understood that all matter herein is to be interpreted merely as illustrative and not in a limiting sense.

I claim:

45 A device of the character described including a base, a round post extending upwardly therefrom, an offset bracket having oppositely extending arms disposed in parallel relation and in different planes to each other, one of said arms being vertically bored and formed with bifurcated 50 clamping portions connected therewith surrounding said post for vertical and circumferential adjustment with respect thereto, a threaded clamping bolt disposed through said bifurcated clamping portions, said vertically bored arm 55 being transversely and vertically bored to respec-

tively support a diamond holder and a locking set screw, and said other arm being vertically and transversely bored to respectively support a diamond holder and a locking set screw for dressing an abrasive wheel to form surfaces at accurately determined angles.
